UNITED STATES PATENT OFFICE.

WILLIAM PRESTON NEAL, OF LOUISVILLE, KENTUCKY.

DESIGN FOR A COSTUMER.

Application filed February 1, 1927. Serial No. 20,573. Term of patent 7 years.

To all whom it may concern:

Be it known that I, WILLIAM P. NEAL, a citizen of the United States, and a resident of Louisville, in the county of Jefferson, State of Kentucky, United States of America, have invented a new, original, and ornamental Design for a Costumer, of which the following is a specification, reference being had to the accompanying drawing forming part thereof.

Fig. 1 is a view in front elevation of a costumer showing my new design.

Fig. 2 is a view in side elevation thereof.

I claim:

The ornamental design for a costumer substantially as shown.

WILLIAM PRESTON NEAL.
